DESIGN.

J. Q. REED.

LADY'S COSTUME.

No. 15,564.

Patented Nov. 18, 1884

UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,564, dated November 18, 1884.

Application filed September 12, 1884. Term of patent 3½ years.

To all whom it may concern:

Be it known that I, JOHN QUINCY REED, of the city, county, and State of New York, have invented and produced a new and original Design for a Pattern of a Lady's Costume, (numbered 9,438;) and I do hereby declare that the engraved prints accompanying this specification convey to any one accustomed to using paper patterns a clear understanding of how a garment made up by the pattern will appear.

The design shows a round walking-skirt and an overdress. The skirt exhibits two plain lower front-draperies extending nearly to the bottom of the skirt and flaring over the center of the front; a deep upper front-drapery displaying a stirring at its center, draping plaits in its back edges, and a wide graduated revers on each half of its lower edge. The overdress exhibits closely-fitted basque-

fronts outlining a deep point at the lower end of the closing and a high arch over the hips; a closely-fitted polonaise-back, which shows a high draping on the outside over the lower part of the center body-seam, draping plaits 25 high up in the front edges of its drapery, and looping at the center of its drapery; a standing collar, and coat-sleeves that display their wrists reversed in cuffs flaring at the back edges, and a gathering and a high roll at the 30 shoulder.

What I claim as my invention, and desire to secure by Letters Patent, is—

The design for a lady's costume, as shown in the engraved prints accompanying this specification. 35

JOHN QUINCY REED.
